ZIPPER SHIRT

Morris L. Kaplan, Hazleton, Pa., assignor to The Shircraft Co., Inc., Hazleton, Pa., a corporation of New York

Application August 23, 1949, Serial No. 111,910

3 Claims. (Cl. 2—128)

1

This invention relates to shirts, particularly to a shirt construction utilizing a slide or zipper fastener.

The principal object of the invention is to provide a positive means of insuring that the zipper or slide fastener construction will be located on the inner side of the front facing edge of the shirt where it will be concealed by the facing and in a position with respect thereto such as will preclude the possibility of the edges of the opening of the shirt becoming entangled in the slider when the latter is manipulated.

Referring to the drawings:

Figure 1 is a sectional view of a portion of the garment in an initial stage of manufacture;

Figure 2 is a similar view showing a slider structure attached to the garment portion shown in Figure 1;

Figure 3 is a view showing the parts in a further stage of the manufacture of the garment, namely the formation of a facing edge of the shirt opening;

Figure 4 is a view similar to Figure 3 showing a locating strip in position within the facing edge; and

Figure 5 is a view of the completed garment showing the slider structure located centrally on the inner side of the facing member by relative movement of the facing member and locating strip.

Referring to Figure 1, the numeral 10 shows one section of a shirt front to which is attached at 11 by stitching an element consisting of a layer of fabric 12 having stitched thereto at 13 a layer of suitable thermoplastic material 14. The element 12 is stitched a short distance back from the free edge 10' of the front shirt section 10.

Referring to Figure 2, adjacent the edge 10' of the section 10 of the garment shown in Figure 1, there is attached a conventional stringer structure indicated at 15 by stitching 16 and 17. Attached to one side of the stringer fabric is a layer of thermoplastic material 15'.

The flat piece shown in Figure 2 is now folded upon itself, as shown in Figure 3, the free edge portion 10' and the section 10 of the fabric being stitched together, as shown at 18, whereupon the section 10 is outfolded upon itself to form the front shirt section and the front edge facing member 19 thereof.

Referring to Figures 3 and 4, it will be noted that the slider structure 15 is positioned at the right-hand end of the assembly, and it is desired to locate the same centrally, as shown in Figure 5, so as to avoid any possibility of the free

edges of the opening of the shirt becoming entangled in the slider structure when the latter is manipulated.

For this purpose, and referring to Figure 4, I insert a stiff metal rod or band indicated at 20, in the opening 21, and by moving the rod or assembly or both relative to each other, the slider structure is positioned centrally, as shown at 22 in Figure 5.

Having located the slider on the inner side of the edge facing 19, sufficiently remote from the free edge 23 of the facing, to preclude entanglement of the free edges of the shirt opening in the slider structure, the garment is ready for pressing. It will be noted that the stringer fabric 15 is folded upon itself, as shown at 24, the line of stitching 16 forming a fold line for thus locating the position of the sliders 25, as shown in Figures 3, 4 and 5.

The rod 20 may be left in position or removed during the pressing operation. In pressing the assembly, sufficient heat is used to fuse the thermoplastic layers 14 and 15. The fused thermoplastic impregnates the adjacent fabric layers and in the case of the stringer fabric 15, causes the same to be embossed with a multiplicity of recesses 26, as shown in Figure 5 by reason of the sliders 25 acting as mold members and embossing the stringer fabric. The recesses or pockets 26 insure that the sliders 25 will always be registered in proper position and whenever the shirt is ironed or pressed, the sliders will be received in the pockets 26 and no embossing of the front surface 26 of the facing member 19 will occur. This is an important advantage in that under all conditions the slider structure will be concealed and the facing 19 will be smooth and plane.

I claim:

1. In the art of shirt manufacture, the steps which comprise securing layers of cloth and thermoplastic material to the cloth layer of a shirt section along a line spaced from the free edge thereof, securing a stringer layer carrying a slide fastener to said shirt section adjacent the free edge thereof and to said cloth and thermoplastic layers, folding the connected layers and connecting the said free edge to a folded-over layer of the shirt section and folding the shirt section outwardly, inserting a stiff band in the opening between the layers and the layer defined by the connected edges of the shirt sections, and moving the layers and band relative to each other to locate the stringer layer and slide fastener centrally of the layers.

2. In the art of shirt manufacture according to claim 1 wherein the layers are pressed after the stringer and slide fastener have been located centrally of the layers and wherein a layer of thermoplastic material is located on the inner side of the stringer layer, and wherein said stringer layer is folded upon itself to dispose the sliders over the stringer layer and the stringer layer embossed by the sliders by subjecting the layers to heat and pressure to provide pockets for registering and receiving said sliders.

3. A facing for the edge of a shirt opening comprising a cloth facing layer, a layer of thermoplastic material enclosed within said facing layer, a cloth layer enclosed within said layer of thermoplastic material, said layers being connected together, the facing layer being connected to a shirt section at one edge on the inner

side of the facing, a free edge of said facing layer being stitched to the facing layer and shirt section on the inner side of the facing layer to thereby enclose said thermoplastic and second-mentioned cloth layers, and a stringer secured to the facing layer on the inner side thereof and disposed centrally of the layers.
